UNITED STATES PATENT OFFICE.

JOHN F. SILLS, OF ALBERTVILLE, ALABAMA.

FINGER-PROTECTOR.

1,109,796.

Specification of Letters Patent. Patented Sept. 8, 1914.

Application filed December 27, 1913. Serial No. 809,019.

To all whom it may concern:

Be it known that I, JOHN F. SILLS, a citizen of the United States, residing at Albertville, in the county of Marshall and State of Alabama, have invented certain new and useful Improvements in Finger-Protectors, of which the following is a specification, reference being had to the accompanying drawings.

10 This invention relates to new and useful improvements in finger protectors for use in picking cotton and the like and the primary object of the invention is to provide a device of this character which may be readily and 15 quickly applied to use and which will positively protect the fingers of the picker while in the act of picking the cotton.

A further object of the invention resides in providing a device formed of flexible material to fit snugly about the finger-tip and 20 still another object resides in providing a device which is simple and durable in construction, inexpensive to manufacture and one which will be very efficient and useful in 25 operation.

With these and other objects in view, the invention consists in the novel features of construction, combination and arrangement of parts as will be hereinafter referred to 30 and more particularly pointed out in the specification and claims.

In the accompanying drawing forming a part of this application, Figure 1 is a perspective view of a protector constructed in 35 accordance with my invention and applied to use on a finger. Fig. 2 is a section therethrough.

In describing my invention, I shall refer to the drawing in which similar reference 40 characters designate corresponding parts throughout the several views and in which 1 indicates the body of the protector, formed preferably of rubber and designed substantially as a thimble. The same is applicable 45 to any finger of the hand, particularly the thumb and fore finger and is of such size as to cover the finger-tip beyond the first joint thereof.

As stated, the body is formed preferably

of rubber, so as to fit snugly about the finger 50 and has formed thereon a plurality of flanges 2, which circumscribe the same, said flanges being arranged in spaced relation to one another, throughout the length of the thimble-like body. Also formed on the flanges 55 in spaced relation to one another and at regular intervals throughout the length thereof, are the integral projections 3 forming studs or prongs on the device.

A device constructed in accordance with 60 this invention will afford ready and easy application to the finger or fingers of the cotton picker and when applied to use, will permit the cotton to be picked from the shell 65 without bruising, scratching or cutting the fingers, as is true under ordinary conditions. Thus, with the use of devices such as described, a greater amount of cotton may be 70 picked in a shorter length of time than is true under present conditions and the difficulties now experienced in the picking of cotton without the use of finger protectors, will be generally obviated.

From the foregoing, it will be seen that I 75 have provided a simple, inexpensive and efficient means for carrying out the objects of the invention and while I have particularly described the elements best adapted to perform the functions set forth, it is obvious that various changes in form, proportion 80 and in the minor details of construction may be resorted to without departing from the spirit or sacrificing any of the principles of the invention.

Having thus described this invention, what 85 I claim is:—

1. A finger protector of the class described including a flexible body of thimble-like design, having a plurality of annular ribs formed thereon, and a plurality of integral 90 projections formed on said ribs, as and for the purpose set forth.

2. A finger protector of the class described including a body of yieldable material designed to form substantially a thimble, a 95 plurality of annular ribs formed at regular intervals throughout the length of the body, and a plurality of integral projections

formed on said ribs, as and for the purpose set forth.

3. A finger protector of the class described including a body of yieldable material designed to form substantially a thimble, a plurality of spaced ribs formed on said body at regular intervals throughout the length thereof, and a plurality of integral spaced

projections formed on said ribs at regular intervals throughout the length thereof.

In testimony whereof I hereunto affix my signature in the presence of two witnesses.

JOHN F. SILLS.
